CLAIM

The ornamental design for a surgical and post surgical patient insulation cap, as shown and described.

DESCRIPTION

FIG. 1 is a perspective view of a surgical and post surgical patient insulation cap showing my new design;

FIG. 2 is a left side elevational view, the opposite side being a mirror image thereof;

FIG. 3 is a front elevational view thereof;

FIG. 4 is a rear elevational view thereof;

FIG. 5 is a reverse perspective view showing the underside; and,

FIG. 6 is a perspective view showing in use thereof.

The broken line showing is for illustrative purposes only and forms no part of the claimed design.
